Specification of Letters Patent.

Patented Nov. 2, 1920.

Application filed March 20, 1919. Serial No. 223,738.

Agile whom it may concern:

Be it known that I, JOSEPH RUSSELL FENWICK, a subject of the King of Great Britain, and resident of Hampton, in the Province of New Brunswick, Dominion of Canada, have invented certain new and useful improvements in Batteries, of which the following is a specification.

This invention relates to improvements in batteries, and the objects of the invention are to so construct the battery in such a manner that it will not deteriorate or become effected to any visible extent by overcharging and which will also give good results on discharge, to eliminate the use of wooden separators between the positive and negative elements, to dispense with the use of thin plates thereby preventing watering and short circuiting due to the separators chafing through or breaking up, and generally to adapt the battery to better perform the functions required of it.

With the above and other objects in view the invention consists essentially of the improved construction hereinafter set forth and described in the following specification and accompanying drawings forming part of the same.

In the drawings,

Fig. 1 is a perspective view of the improved battery, part of the jar being broken away to show the position of the separating walls, and also the location of the positive and negative elements provided with a filling of lead oxid.

Fig. 2 is a sectional plan view of the improved battery.

Fig. 3 is a vertical section of the improved battery.

Fig. 4 is a perspective view of the positive and negative elements showing the manner in which the plates of one element are constructed relatively to the plates of the other elements.

Like characters of reference refer to like parts in the several figures.

Referring to the drawings, A represents a battery of the wet type comprising a jar 10 formed of earthenware or other suitable

material and having a plurality of earthenware dividing walls 11 subdividing the jar into a plurality of compartments 12.

The positive and negative elements B and C are similar in construction, which consists of a plurality of spaced plates 13 which are 55 honeycombed and filled with lead oxid, the said plates being constructed of a suitable conducting material and being connected by a metallic tube 14 adjacent to one end of which a post 15 is located.

The plates 13 of the positive and negative elements B and C are constructed relatively to each other, that is to say that when the two elements are positioned in the jar 10, the elements will be arranged consecutively 65 negative and positive, each plate being in a separate compartment 12.

The compartments are filled with a mixture of sulfuric acid and water of a predetermined gravity and the jar 10 may then be 70 inclosed in a rubber or other suitable jar with the posts 15 of the positive and negative elements B and C extending through the cover of the rubber jar.

I have found that a wet battery of this 75 construction gives exceptionally good results in practice, and the earthenware walls 11, while being very porous do not deteriorate to any visible extent even when overcharging and there is no possibility of the 80 division walls chafing through and resulting in short circuiting and the lifetime of the battery is much greater than the ordinary wet batteries at present in use.

As many changes could be made in the 85 above construction and many apparently widely different embodiments of my invention, within the scope of the claim constructed without departing from the spirit or scope thereof, it is intended that all matter contained in the above specification and accompanying drawings shall be interpreted as illustrative and not in a limiting sense.

What I claim as my invention is:—

A wet battery of the class described, comprising a jar subdivided into a plurality of compartments by porous earthenware walls, positive and negative elements, each com-

prising a plurality of perforated conducting plates with a filling of metallic oxide, the conducting plates of each element being connected by a conducting plate carrying a post, the plates of one element being staggered relatively to the plates of the other element, the plates being designed to be located alternately in adjacent compart-

ments of the jar, as and for the purpose specified.

In witness whereof I have hereunto set my hand in the presence of two witnesses.

JOSEPH RUSSELL FENWICK.
